UNITED STATES PATENT OFFICE.

JACOB OCHSNER, OF ZURICH, SWITZERLAND.

DUMP-CAR.

1,361,608.

Specification of Letters Patent.

Patented Dec. 7, 1920.

Application filed July 26, 1919. Serial No. 313,572.

To all whom it may concern:

Be it known that I, JACOB OCHSNER, a citizen of Switzerland, residing at Zurich, in the Canton of Zurich, Switzerland, have invented certain new and useful Improvements in Dump-Cars, of which the following is a specification.

This invention relates to an improved dumping car and more particularly to a type wherein one or more carriage supports move transversely of the car and carry a bucket, which is mechanically tilted to discharge its contents.

The object of this invention is the provision of a device of the character herein-after set forth, which is capable of discharging quantities of material at a considerable distance from the car proper and by reason of the compact construction, several such units may be independently mounted upon the platform of a single car.

A further object of the invention is to provide an efficiently operated bucket, which by reason of its design is capable of quickly discharging any material within a comparatively short time.

The invention consists in the structural features and combinations of parts herein-after fully described with reference to the accompanying drawings wherein,

Figure 1, is a side elevational view of a car showing two dumping buckets and their supporting parts arranged therein.

Fig. 2, is a vertical sectional view on the lines A—B of Fig. 1, showing the bucket in the tilted or tipped position.

Fig. 3, is a front elevational view of one of the buckets mounted in its supports and held in normal position.

Referring to the drawings *a* indicates a bucket having a cylindrically shaped bottom and outwardly flared sides, the ends however being straight and provided with projecting pivot pins *b*. The bucket *a* is adapted to operate in a transverse direction to the axis of the car upon which it is mounted, in other words the pivotal axis of said bucket *a* is parallel to the axis of the car. A supporting carriage frame *d* is provided with centrally located bearing blocks *c* at opposite sides thereof and raised upon suitable strengthening bars slightly above the plane of said supporting frame *d*. The bearing blocks *c* have vertically extending slots to accommodate the pivot pins *b* of the bucket

a, and it will be noted with reference to the drawings, that the bucket may readily be removed by raising same out of the slotted openings in the bearing block. This construction is particularly desirable when the buckets are loaded elsewhere than on the car, and transported by derrick or other suitable means, and suspended above the bearing blocks until the pivot pins *b* register with the slotted openings and permitted to drop therein.

The supporting carriage frame *d* substantially surrounds the bucket *a* and comprises a rectangularly arranged frame having parallel longitudinal channel beams *q* connected at their ends by bars upon which a series of rollers *e* are mounted. The lower extension of the carriage frame *d* is made up of parallel channel beams arranged at each end of the frame on a plane parallel with the bottom of the bucket *a*. The construction described above provides a substantially rigid supporting carriage frame capable of withstanding any strain to which the latter may be subjected.

The supporting carriage frame *d* is adapted to be guided in its lateral movement and likewise supported by a superstructure *g* mounted transversely of the car upon longitudinally extending I beams *h*. The I beams *h* extend the entire length of the car and as shown in Fig. 1, may support one or more complete dumping devices. The guide frames *g* are arranged at opposite sides of the supporting frame *d* and are provided with transversely extending channel beams *f*. A box beam *f'* is secured to the I beams *h* and is parallel to the upper channel beams *f* having their ends connected by the uprights of *g*. A series of rollers *i* is mounted in each of the box beams *f'* and protrude through slots in the upper face of the beam. The under surface of the channel beam *f* and the upper surface of the lower channel beam of the supporting frame *d* are provided with groove guides *f²* and *d²* respectively, said grooves being adapted to accommodate the rollers *e* and *i*. It will be noted that the rollers *e* are mounted in the movable supporting carriage frame, while the rollers *i* are mounted in a portion of the stationary frame *g*, and in accordance with this construction, when the frame *d* is extended as shown in Fig. 2, the strain of the entire load will come under the channel

beam f . By reason of its rigid connection with the I beams h and platform of the car proper, the strain is evenly distributed throughout the structure.

- 5 Mounted between the stationary box beams f' and journaled therein are winding drums o adapted to receive the conveying and tilting chains p' and p^2 . The bearing shafts of the drums o protrude outside of the 10 frame g and have mounted thereon sprocket wheels l^2 . Endless sprocket chains k connect the sprockets l^2 with small sprocket wheels l' mounted upon and adapted to turn with a crank shaft m the outer end of which 15 is formed as a crank handle. The shaft m is mounted in bearings supported in the channel beam f and is provided with a ratchet disk the teeth of which are adapted to be engaged by pivoted dogs also mounted 20 upon the beam f .

Each of the parallel channel beams q is provided with a hook r depending from the under face of the beam midway of its length thereof, and said hooks are designed to receive 25 the end links of the chains p' and p^2 as described hereinafter. Similar hooks s are secured to the outer edge of the rim of the bucket a , each hook being midway of the side of the bucket and adapted to receive 30 the end link of one of the chains p' and p^2 in accordance with the operation of the device as set forth hereinafter.

The supporting I beams h extend the entire length of the car and each of the outermost members supports the edge of a distributing board t . The board t is inclined from the top of the I beams h to the edge of the car platform, and also extends inwardly from said I beams to a still higher 40 point located midway of the car platform beneath the bucket. A central opening in the inner portion of the board t is provided to accommodate the winding drums o , which is clearly shown in Fig. 2, of the drawings.

45 In the operation of each of the dumping buckets and their traveling supporting carriage frames, the following description will fully disclose the functions of one unit and it will be understood that, any number 50 mounted upon the same car platform will be controlled and operated in the same manner.

When it is desired to dump the material from the bucket a , to the left of the car as 55 shown in Fig. 2, the chains p' and p^2 will be unwound from their respective drums o . The end link of the chain p' carried by the left hand drum will be hooked over the hook r on the right hand beam q of the movable 60 supporting carriage frame d , likewise the end link of the chain p^2 carried by the right hand drum will be hooked over the hook s depending from the left hand side of the bucket a . This will place the carriage supporting frame d and bucket a in a position

to be moved toward the left side of the car and tipped.

The left hand drum is operated by the sprocket chain k and handle m , which is rotated counter clockwise. The winding up 70 of the chain p' about the left hand drum o will draw the carriage frame d toward the left of the car. The chain p^2 extended by the right hand drum o may at this point be wound up about the latter, which will rock 75 the bucket a on its pivots b . The rotation of the sprocket chain k and sprockets l^2 and l' are controlled by the crank handle m , which in the present instance will be moved 80 clockwise.

The material having thus been dumped onto the inclined side of the car will continue its outward travel to the edge of the latter where it will fall to the ground or to a conveyer if one be provided. The return 85 of the bucket to its upright position will be automatic, after release of the chain p^2 , due to the fact that the pivots b are considerably above its center of gravity. The chain p' being unhooked and the end link of the 90 chain p^2 carried by the right hand drum is hooked over the hook r depending from the right hand channel beam q . The crank handle m is again rotated toward the right winding the chain p^2 and drawing the carriage frame g toward the right until its normal 95 position is reached.

It will be understood that by reversing the operations noted above the carriage g may be made to move to the right and the 100 bucket a may be made to dump at the right hand side of the car.

Having described the nature of the invention and its operation, what I claim is,

1. A dumping car, having a superstructure mounted thereon, a carriage frame slidably mounted in said superstructure, anti-friction members carried by the superstructure and carriage frame and adapted to sustain said carriage frame, a hollow container mounted in said carriage frame and having a cylindrical bottom portion terminating in upwardly extending flared sides and end portions having pivots mounted thereon, said pivots being rotatably supported in said 110 carriage frame, and windlasses mounted in a portion of said superstructure and having chains adapted to be wound about said windlasses the free ends of said chains being detachably connected respectively to a portion 115 of the container and carriage, whereby the latter may be moved and the container tilted to discharge its contents.

2. A dumping car, having a superstructure arranged thereon, a supporting carriage frame capable of transverse movement in guides forming part of said superstructure, a bucket pivotally mounted in said supporting carriage and adapted to be tilted 125 therein, means whereby said carriage may 130

be moved in the superstructure, and means whereby the tilting of said bucket may be independently controlled.

3. A dumping car, having a transversely arranged superstructure mounted thereon, a supporting carriage frame adapted to be movably guided and supported by said superstructure, a tilting bucket having pivot pins at each side thereof and open bearings carried by the carriage frame to receive said pivot pins whereby said bucket may be removed from the car and supporting carriage without dismantling any of the adjacent parts.
- 15 4. A dumping car, having a plurality of stationary supporting frames, longitudinally disposed I beams arranged parallel to the axis of the car and adapted to form a bed upon which the stationary supporting frames are transversely mounted, a carriage frame movably mounted in each of said stationary frames, and buckets mounted in said carriage frames and capable of being independently tilted to dump their contents, and 20 mechanical means provided for each unit whereby said bucket may be tilted and each carriage may be moved transversely in said supporting stationary frame.
5. A dumping car, having a longitudinally disposed bed supporting structure, one or 25 more stationary supporting frames fixed to said bed structure and adapted to be located
- transversely of said bed structure, a sliding carriage frame mounted to traverse said stationary supporting frame and having a 35 bucket pivotally mounted therein adapted to have its greatest carrying capacity below the pivots of said bucket, and windlasses mounted in said stationary supporting frame and having chains wound thereon adapted to 40 have the free ends interchangeably connected to the bucket or carriage frame whereby the latter may be extended and the bucket tilted at either side of said car.
6. A dumping car having buckets and 45 supporting carriages capable of being extended to either side of said car, a pair of windlasses mounted on said car and having chains adapted to be wound about each windlass, the free ends of each of said chains 50 adapted to be interchangeably connected to said bucket or carriage, hand cranks journaled in a part of said car and having sprockets mounted thereon capable of being locked in fixed position, and endless sprocket 55 chains connecting said first mentioned sprockets and other sprockets mounted to rotate with said windlasses.

In testimony whereof I have affixed my signature in presence of two witnesses.

JACOB OCHSNER.
